Primary Examiner — Mark A Goodwin*Assistant Examiner* — Adam C Mager(74) *Attorney, Agent, or Firm* — Joseph A. Andelin; Fish IP Law, LLP(57) **CLAIM**

I claim the ornamental design for a wheel rim, as shown and described.

DESCRIPTION

FIG. 1 is a front elevation view of a wheel rim embodying the new design;

FIG. 2 is a top, front, and right-side perspective view thereof; and,

FIG. 3 is a cross-sectional view thereof; taken along the long dash short dash broken line 3-3 in FIG. 1, which forms no part of the claimed design.

The broken lines depicting portions of the wheel rim form no part of the claim.

The hatching lines viewed in FIG. 3 are for illustrating inside portions of the wheel rim and form no part of the claimed design.
